Primary Examiner — Terry A Wallace(74) Attorney, Agent, or Firm — Banner & Witcoff, Ltd.(57) CLAIM

The ornamental design for a storage bag, as shown and described.

DESCRIPTION

FIG. 1 is a top, front, left perspective view of a storage bag showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines within the shaded area represent features that form no part of the claimed design. The storage bag is shown with symbolic breaks in its length. The appearance of any portion of the article between the break lines forms no part of the claimed design.
